CLAIM

The ornamental design for a combined nameplate and mailbox support pole, substantially as shown.

DESCRIPTION

FIG. 1 is a perspective view of a combined nameplate and mailbox support pole showing our new design;
FIG. 2 is a side elevational view thereof showing the side opposite to that shown in FIG. 1;
FIG. 3 is a front elevational view thereof;
FIG. 4 is a rear elevational view thereof;
FIG. 5 is a top plan view thereof; and
FIG. 6 is a bottom plan view thereof.
